Primary Examiner — Susan Moon Lee(74) *Attorney, Agent, or Firm* — Sherrie Flynn; Coleman & Horowitz, LLP(57) **CLAIM**

What is claimed is an ornamental design for an animal interaction device, substantially as shown and described.

DESCRIPTION

FIG. 1 is a right elevational view of an animal interaction device;

FIG. 2 is a left elevational view thereof;
 FIG. 3 is a back elevational view thereof;
 FIG. 4 is a top plan view thereof;
 FIG. 5 is a bottom plan view thereof; and,
 FIG. 6 is a front, top, right perspective view thereof.
 The portions depicted in broken line illustrate parts of the animal interaction device that form no part of the claimed design.
